SAFETY ATTACHMENT FOR CLOTHES WRINGERS

Frederick C. Lindsey, Milwaukee, Wis.

Application July 27, 1934, Serial No. 737,217

5 Claims. (Cl. 68—32)

This invention relates to clothes wringers, and particularly to safety attachments for clothes wringers.

One object of this invention is to provide modern clothes wringers with means for making them safer with respect to injury to the user as well as to the clothing being wrung thereby.

Another object is to provide an improved clothes guarding unit that is attachable to the upper roller-axles of any modern electrically operated or power-operated clothes wringer of the type here shown and briefly described.

Another object is to provide this attachment with an improved attaching means by which it is moved upward and downward with the upper roller so as to keep the brushes or deflectors thereof substantially level with the axis of the upper roller as the latter is raised and lowered in its operation on washed articles of greater or less thickness.

Another object is to utilize the usual roller-end guards as guides for the brackets that support the brushes or clothes deflectors.

Another object is to provide an improved clothes feeding attachment that can be attached quickly and easily to a wringer of the modern type, mentioned, and which includes an improved form of clothes guarding and clothes feeding belt mounted and controlled in an improved manner, whereby the clothes are fed to the rollers without danger to the hands of the operator or to the clothes.

Another object is to provide an improved unitary attachment that includes a combined feed-belt tightener and automatic drain-plate adjuster or reverser.

Other objects and important features are pointed out or implied in the following detail-description, in connection with the accompanying drawings in which:

Fig. 1 is a top plan view of a part of a wringer-frame having my improved clothes-guarding unit fitted in the roller-end guards.

Fig. 2 is a perspective view of one of the sheet metal brush-holding brackets, disconnected.

Fig. 3 is a fragmental sectional view taken along the line 3—3 of Fig. 1.

Fig. 4 is a view, mainly in front elevation, but showing parts of the frame broken away, the lower part thereof in vertical section, a part of the upper clothes-guarding unit broken out, and parts of the lower attachment in section near the middle thereof.

Fig. 5 is a detail sectional view taken along the line 5—5 of Fig. 4.

Fig. 6 is an enlarged sectional view taken in slightly different planes substantially along the lines 6—6 of Fig. 4, the upper clothes-guard being omitted.

Before describing the attachments, the conventional modern wringer will first be described; for though this is of the general type currently on sale, and known by the names "Thor", "Barton", "Easy", "G. E." "Hot Point", "Hibbard's True Value", "Horton", etc.; there are doubtless other types which are more or less modern and to which this invention may not be applicable; but it should be understood that the field of usefulness of this invention is not limited to the several clothes wringers mentioned above.

The wringer-frame is substantially in the shape of a hollow square, its lower or main section A being formed of U-beams, the lower U-beam being inverted so its lower side is open while its upper side has fastener-receiving holes a therethrough. The edges of the uprights are turned inward at a'. The upper removable part of the main frame is shown at B, and is an inverted U-beam having its lower side open to receive the pressure-spring C that bears upon the upper bearing blocks D, in the uprights, as shown in Fig. 6. The lower roller E, of rubber or composition, has its axle journaled in the conventional bearings within the uprights of the frame A—B, its driving axle being shown at e. The upper roller (of conventional material), is shown at F, and its journals f are engaged with the bearing blocks D and thereby pressed towards the lower roller E. A pair of roller-end guards are shown at G, each one being of sheet metal stamped and pressed into substantially U-shape, as more clearly shown in Figs. 3 and 6. Each guard G has a flange g that covers the spaces between the roller ends and the uprights of the main frame; and each member G also has somewhat springy attaching flanges g¹ that interengage with the flanges a' (of the uprights) so as to removably secure them in their respective places. No novelty is claimed for the structure thus far described.

Referring to the reference numerals on the drawings, the invention is described as follows:

To prevent the clothes (being wrung) from wrapping around the upper roller, I provide two deflectors 10 which are preferably in the form of long stiff-bristle brushes supported at opposite sides of the upper roller F and in contact therewith in the horizontal axial plane thereof, their supporting means being the axles of the upper roller in connection with two sheet-metal brackets 55

or carriers 11 which have openings $11a$ therethrough to receive the respective axles therethrough. Each member 11 also has angularly disposed parallel opposite flanges $11b$, and from the edges of these flanges extend two angular arms $11c$, having screw-holes $11d$ through which extend the screws or bolts for securing the brushes 10 thereto; so the latter are securely united with their carriers 11 to form a unitary attachment to the upper roller F ; but it should be understood that the beam B must first be removed, the upper roller next removed, and the axles f passed through the openings $11a$ before the union of the brushes and their carriers is completed; then when the upper roller is again lowered to its operating position, the flanges $11b$ are slid down between the flanges g of the roller-end guards. It will be seen, therefore, that as the upper roller and its axles move upward, the deflectors 10 move upward therewith; and when the upper roller moves downward, the deflectors 10 move downward therewith, always remaining in the proper definite relation to the upper roller, as described.

25 Therefore, if an article of clothing adheres to the upper roller and starts to wrap around it, the deflecting device will push the clothing free from adhering to the roller and permit it to fall and to pass from the wringer in the proper manner.

30 The lower attachment includes a sheet metal base or frame 12 having a bottom or drain-plate formed with oppositely inclined parts $12a$, and a central apertured part $12b$ through which extend thumb-screws or fasteners 13 for securing it on the lower beam of the main frame A , said fasteners also extending through the holes a . The member 12 also includes side-walls $12c$, each having its middle upper part formed with an upwardly opening recess or space $12d$ of the proper size and shape to receive the respective roller end guards, or at least the lower end thereof. Each wall $12c$ is also provided with bearings $12e$, either formed integrally therewith, or united therewith by any proper securing means.

35 A pair of long and slender belt-pulleys 14 have their axles 15 journaled in the bearings $12e$, the middle parts of these pulleys being bulged for a purpose well known by the users of belt-pulleys, and also for the special purpose of making these long slender pulleys relatively light and rigid. The axes of these pulleys are considerably lower than the axis of the lower wringer roller. A belt or feeding apron 15 extends around these pulleys and around the lower wringer roller E , so that its upper reach extends between the lower and upper rollers, while its lower reach is spring-held against the lower side of the lower roller by means of a combined belt-tightener and drain deflector now described as follows:

40 A belt-tightening roller 17 has its journals 18 supported in bearings 19 of a sheet metal spring or flat spring 20 which is secured to a tilting drain-plate 21 and to a rod 22 by any appropriate means, for instance, by flat strips 23 that extend through apertures of the drain-plate 21 and embrace the spring 20 and rod 22 . These members 20 , 21 , 22 and 23 are also preferably soldered or welded together for securing them in fixed relation to one another. To prevent longitudinal movement of the rod 22 and its adjuncts, and to secure it in its effective position, its ends may be bent downward, as shown, and passed into holes $12f$ in the part $12b$ of the base 12 ;

45 but this is only one of a number of ways the same result may be obtained. In this disclosure, however, it should be understood that the holes $12f$ are large enough to permit the rod to be turned as on its longitudinal axis, so the drain-plate 21 can turn therewith from the level position, shown in full lines (Fig. 6) to the inclined position shown in broken lines, and then to the opposite inclined position, according to the direction of rotation of the lower roller E and belt 16 or apron 16 . Assuming that the clothes are fed to the apron 16 at the right side of Fig. 6, the belt traveling in the direction of the straight arrows, the lower roller rotating in the direction of the curved arrow thereon, it is seen that 50 the action or pull of the belt or apron against the roller 17 moves it to the broken line position and tilts the drain-plate 21 to its broken line position; and all the while, the roller 17 remains tightly pressed against the lower reach of the belt 16 so as to tighten it against the lower wringer roller, so the latter exerts frictional pulling action on the lower reach of the belt as well as on its upper reach, thus minimizing the slipping tendency caused by soapy water in 55 the clothes being continually making the rollers slippery.

60 To still further minimize the slipping tendency of the belt, both sides thereof may be roughened or minutely cross-corrugated as indicated at $16a$, but this has not been found essential where the spring 20 is stiff enough to press the roller 17 , and thereby the belt 16 against the lower roller with sufficient force to penetrate the soapy film on the roller E , assuming that such film may 65 have found its way to the lower roller from the edges of the belt 16 . The cross-corrugations $16a$ may be formed of a surface-coat of rubber upon the woven fabric base of the belt, though the invention is not limited to this form of belt. Neither is the invention limited to the other precise details set forth, for the same is susceptible of numerous changes within the scope of the inventive ideas as implied and hereinafter claimed.

45 What I claim as my invention is:

1. In an attachment for a clothes wringer which includes a main frame that comprises a horizontal lower beam and upright beams and also comprises upper and lower rollers having 50 journals journaled in the upright beams; said attachment comprising the combination of a drain-plate provided with means for attaching it to said lower beam, said drain-plate having upright walls at its opposite ends, each of said 55 walls having bearings at opposite end portions, long and slender pulleys journaled in said bearings of the walls, a clothes-feeding belt on and around said pulleys and adapted to receive said lower roller therethrough between its upper and 60 lower reaches from one to the other of said pulleys, a spring having upwardly pressed bearings on its ends and provided with means supporting it on said drain plate and between said walls, and a belt-tightening roller having journals 65 seated in the bearings of said spring and thereby pressed upward against said belt.

2. The combination defined by claim 1, said means including a tiltably mounted second drain-plate to which said spring is secured so that oppositely directed movements of said belt will move said belt-tightening pulley in opposite directions and thereby tilt said second drain-plate to oppositely inclined positions.

3. The combination with a clothes wringer 75

which includes a frame having a horizontal lower part with uprights on its ends, upper and lower rollers having journals, and bearings for said journals in said uprights; of an attachment including belt pulleys connected with said frame and disposed at opposite sides of said rollers, a clothes-feeding belt around said pulleys and having a lower reach under the lower roller and an upper reach between the lower and upper rollers, and a belt-tightening roller provided with springy means in said frame to yieldingly compensate for wear of the journals of said lower roller and said belt-tightening roller while spring-pressing it upward against the lower reach of the belt and thereby press the lower reach upward against said lower roller.

4. The combination defined by claim 7, a drain-plate under said belt said means including a second drain-plate tiltably mounted over the first said drain-plate and operable for movement to oppositely inclined positions, and upwardly spring-pressed bearings mounted on said second drain-plate and rotatably supporting said belt-tightening roller while pressing it against said belt so that the belt's movements in opposite directions effects bodily movement of the belt-

tightening roller in opposite directions and thereby tilts the second drain-plate to its oppositely inclined positions.

5. In combination with a clothes wringer which includes a main frame that comprises a horizontal lower beam and upright beams and also comprises upper and lower rollers having journals journaled in the upright beams; a combined feeding and guiding attachment which comprises the sub-combination of a drain plate provided with means for attaching it to said lower beam, said drain-plate having upright walls at its opposite sides, each of said walls having a recess containing a roller-end guard that normally has adjacent ends of the upper and lower rollers extending thereinto so as to prevent material being wrung from protruding beyond the ends of the rollers, long and slender belt-pulleys having journals rotatably supported by said walls of the drain-plate, and a clothes-feeding belt on and around said pulleys and normally having said lower roller therethrough between its upper and lower reaches that extend from one to the other of said long and slender pulleys.

FREDERICK C. LINDSEY. 25
